UNITED STATES PATENT OFFICE.

RALPH F. ROGERS, OF CHICAGO, ILLINOIS.

MOTORCYCLE SIDE CAR.

1,318,924.

Specification of Letters Patent.

Patented Oct. 14, 1919.

Application filed May 27, 1918. Serial No. 236,793.

To all whom it may concern:

Be it known that I, RALPH F. ROGERS, a citizen of the United States, residing at Chicago, in the county of Cook and State of Illinois, have invented a new and useful Improvement in Motorcycle Side Cars, of which the following is a specification.

My invention relates to certain new and useful improvements in motorcycle side-cars and is fully described and explained in the specification and shown in the accompanying drawings, in which—

Figure 1 is a side elevation of the device; Fig. 2 a rear elevation; Fig. 3, a top plan 15 of the running gear; Fig. 4, a section on the line 4 of Fig. 3; Fig. 5, a section on the line 5 of Fig. 2; Fig. 6, a top plan of a modified form of the outer end of the axle and its connections; Fig. 7, a vertical section 20 through the axle showing the adaptation of the structure to use with an extension axle.

The present structure is designed to simplify the running gear to the greatest possible extent, omitting all unnecessary parts, 25 thus saving weight and reducing the cost.

In the drawings, 8 is the axle, preferably of tubular form. At its inner end is a forging 9 containing a socket which receives the tubular axle, a vertical longitudinally-extending plate-portion 10 to which is adjustably secured a socket member 11 (Figs. 2 and 5), the rear end of the plate-portion being turned outwardly to form an ear 12 (Figs. 2, 3 and 5), to which is bolted a pin 35 13 supporting a spring-shackle 14. The socket member 11 is attached to a ball-member 15 secured to the motorcycle, the vertical adjustment of the socket member upon the plate of the forging permitting the axle to 40 be maintained perfectly horizontal in spite of variations in the position of the ball-member on motorcycles of different constructions. Since however the extreme difference in vertical position of the ball-member in 45 motorcycles now on the market is not over three-fourths of an inch in either direction from a mean position, the adjustment of the socket member 11 may be dispensed with, the axle being inclined slightly, and the 50 body either being adjusted to compensate for the inclination of the axle or not as desired. 16 is a brace attached by a bracket 17 to the axle and running upward and forward to a point adjacent the seat-post cluster 55 of the motorcycle. This brace is preferably

curved to afford a limited elasticity so that the small vibrations of the side-car running gear from the road are cushioned thereby before reaching the motorcycle. On the outer end of the axle is a forging 18 having 60 a split socket 19 at its long end, which is clamped to the end of the axle. The forging has an upwardly-extending portion 20 into which is driven an axle-pin 21 having a taper fit in the socket and held in place by a 65 nut 22. A wheel is journaled on this axle pin in the usual manner. The forging 18 has a rearwardly-extending spring-supporting-pin 23 between which and the shackle 14 is carried a semi-elliptic spring 24.

25 is the fender which is carried by three braces 26, two horizontal and one vertical, on opposite sides of the wheel, the three braces on each side meeting in fittings 27 which are carried by the two ends of the 75 axle-pin 21 and held in place by nuts. The fender can thus be readily removed for work on the tire. The fender is kept from oscillating or swinging around its support by a brace 28 on the inside of the fender 80 which is held in place by a screw 29 entering the lower part of the forging 18.

When it is desired to employ an extension axle with this structure, the axle-pin 21 is knocked out and an extensible member 30 85 is slipped into the tubular axle 8. A forging 31 is carried on the end of the extensible member, and the axle-pin can be inserted therein precisely as in the forging 18. By this arrangement the side-car is adapted for 90 use with the extension axle, for which there is considerable demand, because for certain particular uses it is highly desirable, but which is, in point of fact, very little used. In accordance with present practice a motorcycle must be made either with or without an extension axle. If made with an extension axle a very considerable weight is added, and yet the extension feature is seldom used, and in many cases never 95 used. With my arrangement, on the contrary, there is no added weight whatever excepting when it is actually desired to employ the extension feature, for when the extension is not to be actually used the extension axle will be removed bodily, and therefore it will be possible with my structure to avoid the now common practice of carrying around a heavy extension axle in unextended condition.

110

The forging 18 has projecting forward ears 32 (Figs. 1 and 4) to which is pivotally secured a forging 33 carried by the rear end of a diagonal bar 34, preferably of rear-
wardly-open channel iron, the diagonal bar being curved at 35 and attached to the lower forward portion of the motorcycle frame. In fitting a side-car to various motorcycle frames, there is some little variation in the 10 distance between the forward and rear points of attachment of the side-car, and also a small variation in the vertical position of the forward attachment. The pivotal arrangement illustrated will amply 15 compensate for these variations, but in the alternative the rather simpler construction of Fig. 6 may be employed. In it, the forging 18 is provided with a squared portion 36 extending diagonally forward in the line of 20 the diagonal bar 34 and rigidly bolted in place therein. With this arrangement the natural resilience of the bar 34 is relied upon to compensate for variations in the distance between the points of attachment of 25 the side-car frame.

A cantaliver spring 37 is secured by a clamp 38 to a central point on the axle 8 and runs forward therefrom. It passes underneath the diagonal bar 34 and is secured 30 thereto by a clamp 39 and its end extends upwardly, being attached to the forward end of the body 40. In assembling, the clamp 39 is tightened up after the diagonal bar has been adjusted to place.

The body itself is of novel form, being 35 principally distinguished, from a mechanical point of view, by the fact that it has a long rear projection 41 behind the seat, in which projection the heavy accessories, such 40 as a spare tire, and other heavy luggage, can be carried. This results in making it possible to secure the axle substantially in line with the axle of the rear wheel of the motorcycle, to advance the seat in the side- 45 car well forward to one side of the seat of the motorcycle, and, at the same time, through the proper placing of the extra weight of a spare tire, luggage, etc., at the extreme rear, to throw the center of gravity 50 of the side-car well back, so that the danger of upsetting in rounding corners is reduced to a minimum.

The structure herein described has not only the obvious advantages of extreme simplicity and light weight, but is adapted to 55 an extraordinary extent to be knocked down for shipment. The diagonal bar is readily disconnected from the outer end of the axle and both the diagonal bar and axle can be 60 very quickly disengaged from the body. The wheel can be packed in the body itself and the axle and diagonal bar will simply form straight pieces which can be packed at will either in the body or beside it in a 65 rectangular crate or box. The present de-

vice, therefore, can be packed in a much smaller package than is now possible with devices of this character.

I realize that considerable variation is possible in the details of the construction 70 herein shown, and I do not intend to limit myself thereto, except as pointed out in the following claims, in which it is my intention to claim all the novelty inherent in the device as broadly as is permitted by the 75 state of the art.

What I claim as new and desire to secure by Letters Patent, is:—

1. A motorcycle frame comprising an axle 80 transverse to the motorcycle frame and attached to the rear thereof, and a diagonal bar running from the outer end of the axle to a forward point on the motorcycle frame, the axle and diagonal bar forming with the motorcycle frame a substantially horizontal 85 rigid triangle, and a front spring running forwardly from a central point in the diagonal bar and backward for attachment to the axle.

2. A motorcycle side-car running gear, 90 comprising an axle transverse to the motorcycle frame and a diagonal bar extending forwardly from the outer end of the axle to a forward point on the motorcycle frame, the axle and diagonal bar forming with the 95 motorcycle frame a triangle, a rear body spring having a two-point bearing on the rear axle and a front spring running forward from a central point on the diagonal bar.

3. A motorcycle side-car running gear having a two-bar frame consisting of an axle at the rear and a diagonal bar running 100 from the outer end of the axle to a forward point on the motorcycle frame, a spring affording a rear support for a body and connected thereto at one point and having its 105 ends carried by the rear axle, and a central longitudinally extending spring furnishing a support for the front of the body and secured to a central point in the diagonal bar.

4. A motorcycle side-car running gear having a two-bar frame consisting of an axle at the rear and a diagonal bar running 110 from the other end of the axle to a forward point on the motorcycle frame, spring means affording a two-point support for a body carried by the rear axle, and a front spring 115 affording one-point support for the body running from the rear axle beyond the diagonal bar, and secured to both.

5. A knock-down motorcycle side-car frame, consisting of an axle adapted for attachment adjacent the rear of the motorcycle, a substantially horizontal diagonal bar detachably and flexibly connected to the outer end of the axle and running to a forward point on the motorcycle frame, whereby the motorcycle frame serves to form 125 with said axle and diagonal bar a rigid tri- 130

angle free from other longitudinal connections adjacent the outer end of the axle and bar.

6. A side-car frame comprising an axle 5 transverse to a motorcycle frame and attached to the rear thereof, and a substantially horizontal diagonal bar running from the outer end of the axle to a forward point on the motorcycle frame, the diagonal bar 10 and axle being adapted to yield in the horizontal plane to accommodate themselves to motorcycles of different distances between points of attachment.

7. A side-car frame comprising an axle 15 transverse to a motorcycle frame and attached to the rear thereof, and a diagonal bar running from the outer end of the axle to a forward point on the motorcycle frame, the diagonal bar and axle being adapted to 20 yield in the horizontal plane to accommodate themselves to motorcycles of different distances between points of attachment, and a front spring connected to both axle and di-

agonal bar, and extending forward of a central point in the diagonal bar. 25

8. A motorcycle side-car frame having a hollow rear axle, an axle-pin supporting member at one end thereof, an extension axle telescoping in the main axle and having a generally similar axle-pin supporting member, and an axle-pin adapted to be supported in either of said members whereby the extension axle can be removed when its use is unnecessary. 30

9. A motorcycle side-car running gear, 35 comprising an axle transverse to the motorcycle frame and a diagonal bar extending forwardly from the outer end of the axle to a forward point on the motorcycle frame, the axle and diagonal bar forming with the 40 motorcycle frame a substantially horizontal rigid triangle, a rear body spring having a two-point support on the rear axle and a front spring having a one-point support centrally of the diagonal bar.

RALPH F. ROGERS.
